CLAIM

The ornamental design for an ear drop applicator, as shown and described.

DESCRIPTION

1. Ear drop applicator

1.1 : Top

1.2 : Perspective top rear view

1.3 : Side view

1.4 : Back

1.5 : Perspective top front view

An ear drop applicator for the application of ear drops, which comprises a tray for receiving a bottle of ear drops placed therein, wherein the tray comprises a spout for inserting into an ear canal and through which the ear drops can pass from the bottle into the ear canal; the second side view is omitted because it is a mirror view of 1.3.
